UNITED STATES PATENT OFFICE.

JOHN J. TATUM, OF BALTIMORE, MARYLAND, ASSIGNOR TO PETER H. MURPHY, OF PITTSBURGH, PENNSYLVANIA.

CAR-ROOF.

1,052,102.

Specification of Letters Patent.

Patented Feb. 4, 1913.

Application filed September 26, 1907. Serial No. 394,764.

To all whom it may concern:

Be it known that I, JOHN J. TATUM, a citizen of the United States, residing at Baltimore, State of Maryland, have invented 5 certain new and useful Improvements in Car-Roofs, of which the following is a specification.

In actual practice it is found that the roof of a freight car requires more attention 10 and repairs than any other part of the car, as the maintenance of a rain and snow tight roof is essential, and the conditions of service are severe. To maintain the seams between the roof sheets tight and to properly 15 and securely attach a roof to a car is one of the most difficult problems that confronts a car builder inasmuch as the "weaving" of a car in transit; the jacking of the car for repairs and the overhang of the cars on 20 sidings has a tendency to twist the roof sheets apart and to tear them from their fastenings at the eaves of the car.

The object of my invention is to overcome 25 the loosening of the roof sheets at the eaves and at the same time to obviate some of the strain on the seam between the sheets by changing the structure of the joints between the several sheets, and by securing the sheets at the eaves of the car by means of 30 what may be called a sliding hinge joint whereby a movement at the outer ends of the sheets is permitted without transmitting any strain or stress to the fastening means.

My invention consists also in a car roof 35 comprising a series of sheets with a loose sliding rain and snow proof joint between them.

My invention consists further of the parts 40 and combination of parts as will be more fully hereinafter pointed out.

In the accompanying drawings, Figure 1 is a top plan view of a freight car (broken away) provided with a roof embodying my invention; Fig. 2 is a perspective view of 45 one of my improved roof sheets provided with one form of fastener; Fig. 3 is a perspective view of roof sheets provided with another embodiment of my invention; Fig. 4 is a perspective view of another form of 50 my improved roofing sheet; Fig. 5 is a perspective view of a car roof covering, broken away, showing my improved roof sheet seam joint, and Fig. 6 is a detail sectional view through the ridge of the car roof illustrating

the joint between the sheets on opposite 55 sides of the roof.

Fig. 1 shows a car body 1 having a wooden roof substructure 2, and roof sheets 3 arranged thereon, the roofing sheets being arranged in two rows lengthwise of the car, 60 one row on each side of the ridge, with their ridge ends hooked together, and with their side edges rebent and interlocked to form loose water tight joints.

The roofing sheets are each provided with 65 a depending flap 4 at its outer end which is rebent as shown in the several figures forming a pocket in which a rod 5 is placed. It will be seen in the forms of roof sheets shown in Figs. 2 and 3 that the depending 70 flap is first bent outward as at 6, thence downward as at 7 and thence inward and thence upward as at 8 in substantially the plane of the under face of the flap and extends up back of the flap whereby the pocket 75 and the rod are positioned in front of the flap thus obviating any projection on the inner face of the flap whereby it may fit snug against the fascia of the car to prevent rain, snow and cinders from entering under 80 the edge of the roof.

In Fig. 3 the eye of the rod is shown as elongated and in line with the pocket in the flap of the sheet; the eyes of the rods of adjacent sheets overlap and are held by a bolt, 85 screw or staple common to both.

As will be seen the construction of the end flap of the roofing sheet provides a sliding interlock and a hinge joint for the sheet whereby the sheet may twist, buckle and 90 slide, sufficiently to take up all twisting, sagging, weaving and strains from jacking of the car without loosening the fastening or the roofing sheets.

It will be understood that I may provide 95 one side of the end sheet of the roof with the fastener rod thereby forming a hinge joint for the roof at the end of the car.

The side seams or joints between adjacent roof sheets by bending up the side margins 100 of the sheets in the form of flanges or "sheds" which when interlocked form hollow flexible and slidable seams.

The sub-structure immediately under the end of each hollow seam is covered by a 105 flat piece of metal 11 for some distance back from the eaves of the car to protect it from rain, snow and cinders. One edge of the

sheets is bent upward to form the wall 14, thence horizontally as at 15, substantially parallel with the main body of the sheet, and thence rebent downward, as at 16, to 5 form a "shed", the rebent portion terminating a comparatively short distance above the main sheet. The other edge of the sheet is bent upward as at 17 (shown in the drawing as slightly inclined) thence rebent 10 to form an upright edge 18 and thence bent inward as at 19 and terminating in an upturned lip 20, thereby forming a groove under the shed formed by the wall 18 and portion 17, into which the edge of an adjacent sheet (bent in accordance with my invention) is movably secured. The inclination of the portion 17 provides for an increased space between the body of the sheet and the joint whereby space is found 15 for the relative movement of the sheets without forming too flat a bend of the metal at the juncture of the walls 17 and 18. The ridge end of the sheet is provided with an upstanding inverted U flange or upward 20 turn bend 12 which is adapted to fit over a similar bend in a sheet on the opposite side of the car roof as shown in Fig. 6.

As will be seen from the drawings, each sheet of the roof has a comparatively liberal 25 lateral play or movement with respect to the other sheets of the roof. In actual practice, there is about one-quarter of an inch play as the clearance between the walls 14 and 16 and the walls 18 and 20 and when 30 it is considered that there are usually eighteen sheets on each side of a car, it will be seen that I have made ample allowance for "give" and "take" in the roof to accommodate the "weaving", twisting and swaying 35 of the car. Such give and take also provides for the automatic adjustment of the roof in case a car is left on a siding inclined transversely on which the upper portion of the body of the car is inclined to 40 hang over.

This construction of roof has, from practical experience, been found to obviate the objections heretofore experienced in other constructions of roof and its use results in 45 a material reduction in roof repair expenses as well as a resultant reduction for claims for goods damaged by roofs springing a leak in transit.

It is obvious that changes may be made in 50 the details of construction without departing from the spirit of my invention, hence I do not wish to be limited to the use of the details shown.

What I claim and desire to secure by Letters Patent is:

1. A car roof comprising a series of roofing sheets flexibly connected at their side edges and having their ends bent down at the eaves forming a depending flap, which 55 flaps are bent near their lower edges out-

ward, thence downward, thence inward and thence upward against the inner face of the flap, thus forming loops at the bottom of each flap, and an independent rod secured loosely in each loop and provided at each 70 end with an elongated eye, the eyes of the adjacent ends of the rods overlapping, and a bolt passing through the overlapping eyes and constituting a common means for securing the ends of adjacent rods. 75

2. A sheet for a car roof, one edge of which is rebent to form a shed and the other edge bent to form an inverted shed, and an intermediate portion of the sheet bent to form a shed over the inverted shed, one wall 80 of the intermediate bend being on an incline to the sheet, whereby a clearance space is formed to provide for movement of an adjacent sheet transverse of the sheet.

3. A sheet for a car roof, one edge of which is rebent to form a shed and the other edge rebent to form an inverted shed, and an intermediate portion rebent to form a shed, wider at the bottom than at the top, over the inverted shed, whereby a clearance 90 space is formed to permit of movement of an adjacent sheet transverse of the shed. 95

4. In an outside metal car roof, roof sheets having upstanding flanges along their two side margins, said flanges being rebent and 100 interlocking to form flexible seams, one of said upstanding side marginal flanges on said sheets being bent inwardly at the top and thence downwardly and terminating above the roof sheet, and the other of said 105 upstanding marginal flanges being bent outwardly at the top and thence downwardly and terminating in a lip turned under the lower edge of the first-named flange of an adjacent sheet.

5. In an outside metal car roof, roof sheets having upstanding flanges along their two side margins, said flanges being rebent and interlocking to form flexible 110 seams, one of said upstanding side marginal flanges on said sheets being bent inwardly at the top and thence downwardly and terminating above the roof sheet, and the other of said upstanding marginal flanges being bent outwardly at the top and thence downwardly and terminating in a lip turned under the lower edge of the first-named flange of an adjacent sheet, said upstanding flanges being spaced apart at their bases in 115 assembled position, whereby they may move relative to each other without flexing the flanges.

6. In an outside metal car roof, roof sheets having upstanding flanges along their two side margins, said flanges being 120 rebent and interlocking to form flexible seams, one of said upstanding side marginal flanges on said sheets being bent inwardly at the top and thence downwardly and terminating above the roof sheet, and the other 125 130

of said upstanding marginal flanges being bent outwardly at the top and thence downwardly and terminating in a lip turned under the lower edge of the first-named flange 5 of an adjacent sheet, and said roof sheets being rebent at the eaves to movably engage fastening means.

In testimony whereof I affix my signature in presence of two witnesses.

JOHN J. TATUM.
